UNITED STATES PATENT OFFICE.

GEORGE A. MORONEY, OF PHILADELPHIA, PENNSYLVANIA.

DESIGN FOR A BOX FOR SOUVENIR PICTURES AND THE LIKE.

Application filed August 12, 1925. Serial No. 14,401. Term of patent 3½ years.

To all whom it may concern:

Be it known that I, GEORGE A. MORONEY, a citizen of the United States, residing at Philadelphia, in the county of Philadelphia and State of Pennsylvania, have invented a new, original, and ornamental Design for a Box for Souvenir Pictures and the like, of which the following is a specification, reference being had to the accompanying drawing, forming part thereof.

The figure is an isometric view of a box for souvenir pictures and the like showing my new design.

I claim:

The ornamental design for a box for souvenir pictures and the like, as shown.

GEORGE A. MORONEY.
